UNITED STATES PATENT OFFICE.

CHARLES BURTON RISLEY, OF PRINCETON, INDIANA.

BOILER-TUBE CLEANER.

SPECIFICATION forming part of Letters Patent No. 734,613, dated July 28, 1903.

Application filed March 18, 1903. Serial No. 148,349. (No model.)

To all whom it may concern:

Be it known that I, CHARLES BURTON RISLEY, a citizen of the United States, residing at Princeton, in the county of Gibson and State 5 of Indiana, have invented certain new and useful Improvements in Boiler-Tube Cleaners; and I do hereby declare the following to be a full, clear, and exact description of the invention, such as will enable others skilled 10 in the art to which it appertains to make and use the same.

This invention relates to cleaners for boiler tubes or flues; and it consists in the novel construction and combination of the parts 15 hereinafter fully described and claimed.

In the drawings, Figure 1 is a section through the boiler-tube cleaner. Fig. 2 is an end view of the boiler-tube cleaner.

A is a bend-pipe, having two branches 20 a and b.

B is a steam-jet pipe screwed or otherwise securely fastened to the pipe A and preferably arranged to point up the branch a.

C is a steam-pipe connected to the jet-pipe 25 B in any approved manner. The pipe C is connected with the boiler in any convenient way, such as by a flexible pipe, and it is provided with a regulating-valve of approved construction.

The branch a is provided with an enlargement or mixing-chamber D, arranged around the jet-pipe B and extending for a short distance in advance of its orifice. The two branches a and b are provided with similar 30 heads or nozzles E and F for engaging with the fire-tubes of the boiler. These heads are removable and are secured in position by set-screws e. Each head has a flange h for bear-

ing against the end of the boiler-tube, and its end portion is tapered, so that it may enter 40 the boiler-tube freely. The branch b is provided with a socket g, which slips over a part h' on the branch a, so that the two parallel branches may be slid closer together or farther apart to suit the tubes of the boiler to 45 which the device is to be applied. G is a screw for securing the two branches together after their position has been adjusted.

The device is used by applying it to two adjacent boiler-tubes and admitting steam 50 through the jet-pipe. The steam-jet draws the hot gases of the furnace through the tube b and forces them through the tube a. The hot gases and steam become intimately mixed 55 in the mixing-chamber D before being forced into the boiler-tube to be cleaned, and the steam is thereby dried and superheated, so that it does not deposit moisture upon the sides of the said boiler-tube.

What I claim is—

In a boiler-tube cleaner, the combination, 60 with a bend-pipe provided with nozzles at its ends for engaging with two fire-tubes, the outlet branch of the said bend-pipe having also a spheroidal mixing-chamber of larger diameter than the outlet-nozzle; of a straight steam-jet pipe secured to the rear end of the said 65 outlet branch and projecting axially of the same part way through the said mixing-chamber.

In testimony whereof I affix my signature in presence of two witnesses.

CHARLES BURTON RISLEY.
